UNITED STATES PATENT OFFICE.

HENRY E. HENNINGTON AND CHARLEY H. BLAKE, OF CRANDALL, AND MORRIS V. GILL, DECEASED, LATE OF CRANDALL, MISSISSIPPI, BY FLORA LEE GILL, ADMINISTRATRIX, OF CRANDALL, MISSISSIPPI.

STEAM SEPARATOR.

Application filed December 5, 1925. Serial No. 73,522.

This invention relates to certain improvements in steam separators and has relation more particularly to a device of this kind of a deflector type and it is an object of the invention to provide a separator of this kind constructed in a manner whereby the steam emitted therefrom is free of moisture.

The invention consists in the details of construction and in the combination and arrangement of the several parts of our improved steam separator whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawings, wherein:—

Figure is a view in perspective with a portion broken away of a separator constructed in accordance with an embodiment of our invention;

Figure 2 is a longitudinal vertical sectional view taken radially through the structure as illustrated in Figure 1;

Figure 3 is a sectional view taken substantially on the line 3—3 of Figure 2.

As disclosed in the accompanying drawings, 1 denotes an elongated hollow member of requisite dimensions and preferably cylindrical in form and having its opposite ends closed.

This member 1 in practice is preferably horizontally disposed and extending within the member 1 through a head 2 is an inlet pipe 3, said pipe extending beyond the longitudinal center of the member 1 but having its inner end spaced from the opposite head 4 of the member. The pipe 3 is in the lower portion of the member 1 and is radially arranged with respect to the outlet pipe 5 extending within the member 1 through the head 4 and at the upper portion thereof, with the inserted end of the pipe 5 extending beyond the longitudinal center of the member 1 but spaced from the head 2.

The inlet pipe 3 is adapted to be suitably connected with the desired source of steam supply while the outer end of the outlet

pipe 5 is adapted to be suitably connected with an engine or the like.

The inserted end of the pipe 3 extends within a lower inlet chamber 6 provided by a vertical partition 7 extending transversely across the lower portion of the member 1 and a horizontally disposed baffle plate 8 interposed between the upper marginal portions of the partition 7 and the head 4. The plate 8 is spaced from the peripheral wall of the member 1 to provide elongated ports 9 through which steam passes upwardly into the circulation chamber 10.

The inserted end of the outlet pipe 5 extends within the outlet chamber 11 provided by the partition 12 intersecting the upper portion of the member 1 and by the substantially concavo convex bottom plate 14 interposed between the lower marginal portion of the partition 12 and the head 2. The steam within the circulation chamber 10 passes within the outlet chamber 11 through the vertically disposed ports 15 provided in the plate 14 at opposite sides of the outlet pipe 5.

It is to be noted that the chambers 6 and 11 are arranged at opposite end portions of the member 1 with the partitions 7 and 12 in spaced relation lengthwise of the member 1 so that the chamber 10 extends from one end of the member 1 to the other.

In communication from below with the chambers 6, 10 and 11 are the trap lines 16 common to the line 17 having interposed therein a drain cock 18 of any preferred type.

The circulation of the steam through our improved separator is clearly indicated by the arrows in Figures 2 and 3 of the drawings and this circulation is such as to assure effective separation of all moisture from the steam so that the steam emitted through the pipe 5 is dry.

It has been fully demonstrated in practice that our improved separator operates to advantage under most adverse conditions, the structure of the separator preventing water passing therethrough even though the boiler is overflowing.

From the foregoing description it is thought to be obvious that a steam separator constructed in accordance with our inven-

tion is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as hereinafter claimed.

We claim:—

1. A steam separator comprising an elongated tubular member having a steam inlet chamber in one end and a steam outlet chamber in the opposite end, said chambers being substantially at opposite sides of the axial center of the member and spaced one from the other at all points, the remaining portion of the interior of the member constituting a circulating chamber, a wall of the inlet chamber having ports in communication with the circulating chamber, the outlet chamber also having ports in communication with the circulating chamber, an inlet pipe extending within the circulating chamber and delivering within the inlet chamber, and an outlet pipe extending within the circulating chamber and leading from the outlet chamber.

35   2. A steam separator comprising an elongated tubular member having a steam inlet chamber in one end and a steam outlet chamber in the opposite end, said chambers being substantially at opposite sides of the axial center of the member and spaced one from the other at all points, the remaining portion of the interior of the member constituting a circulating chamber, a wall of the inlet chamber having ports in communication with the circulating chamber, the outlet chamber also having ports in communication with the circulating chamber, an inlet pipe extending within the circulating chamber and delivering within the inlet chamber, and an outlet pipe extending within the circulating chamber and leading from the outlet chamber, the inlet chamber being in the lower portion of the member and having ports in its top wall at a point adjacent a wall of the member, the outlet chamber being in the upper portion of the member and having ports in a vertical wall.

55 3. A steam separator comprising an elongated tubular member having a steam inlet chamber in one end and a steam outlet chamber in the opposite end, said chambers being substantially at opposite sides of the axial 60 center of the member and spaced one from the other at all points, the remaining portion of the interior of the member constituting a circulating chamber, a wall of the inlet chamber having ports in communication with the circulating chamber, the out- 65

let chamber also having ports in communication with the circulating chamber, an inlet pipe extending within the circulating chamber and delivering within the inlet chamber, and an outlet pipe extending within the circulating chamber and leading from the outlet chamber, the inlet chamber being in the lower portion of the member and having ports in its top wall at a point adjacent a wall of the member, the outlet chamber being in the upper portion of the member and having ports in a vertical wall, the inlet pipe and the outlet pipe being reversely disposed. 70 75

4. A steam separator comprising an elongated tubular member having a steam inlet chamber in one end and a steam outlet chamber in the opposite end, said chambers being substantially at opposite sides of the axial center of the member and spaced one from the other at all points, the remaining portion of the interior of the member constituting a circulating chamber, a wall of the inlet chamber having ports in communication with the circulating chamber, the outlet chamber also having ports in communication with the circulating chamber, an inlet pipe extending within the circulating chamber and delivering within the inlet chamber, and an outlet pipe extending within the circulating chamber and leading from the outlet chamber, the inlet chamber being in the lower portion of the member and having ports in its top wall at a point adjacent the wall of the member, the outlet chamber being in the upper portion of the member and having vertically disposed ports in a wall thereof at opposite sides of the outlet pipe.

5. A steam separator comprising an elongated tubular member having a steam inlet chamber in one end and a steam outlet chamber in the opposite end, said chambers being substantially at opposite sides of the axial center of the member and spaced one from the other at all points, the remaining portion of the interior of the member constituting a circulating chamber, a wall of the inlet chamber having ports in communication with the circulating chamber, the outlet chamber also having ports in communication with the circulating chamber, an inlet pipe extending within the circulating chamber and delivering within the inlet chamber, an outlet pipe extending within the circulating chamber and leading from the outlet chamber, the inlet chamber being in the lower portion of the member, the top wall of the inlet chamber being spaced from the peripheral wall of the member to provide elongated ports affording communication between the inlet chamber and the circulating chamber, the outlet chamber being in the upper portion of the member and having ports in a vertical wall. 130

6. A steam separator comprising an elongated tubular member having a steam inlet chamber in one end and a steam outlet chamber in the opposite end, said chambers being substantially at opposite sides of the axial center of the member and spaced one from the other at all points, the remaining portion of the interior of the member constituting a circulating chamber, a wall of the 10 inlet chamber having ports in communication with the circulating chamber, the outlet chamber also having ports in communication with the circulating chamber, an inlet pipe extending within the circulating chamber 15 and delivering within the inlet chamber, the outlet chamber also having ports in communication with the circulating chamber, an inlet pipe extending within the circulating chamber and delivering within the inlet chamber, an outlet pipe extending within the circulating chamber and leading from the outlet chamber, trap lines in communication with the lower portions of the chambers, and a valve 20 controlled line common to all of the trap lines.

7. A steam separator comprising an elongated tubular member having a steam inlet chamber in one end and a steam outlet chamber in the opposite end, said chambers be- 25

ing substantially at opposite sides of the axial center of the member and spaced one from the other at all points, the remaining portion of the interior of the member constituting a circulating chamber, a wall of the 30 inlet chamber having ports in communication with the circulating chamber, the outlet chamber also having ports in communication with the circulating chamber, an inlet pipe extending within the circulating chamber 35 and delivering within the inlet chamber, an outlet pipe extending within the circulating chamber and leading from the outlet chamber, trap lines in communication with the lower portions of the chambers, and a valve 40 controlled line common to all of the trap lines, the bottom wall of the outlet chamber having its inner surface concave.

In testimony whereof we hereunto affix our signatures.

HENRY E. HENNINGTON.
